JOHN MARTINO, JACOB BEESLEY, AND JOHN CURRIE, OF PHILADELPHIA, PENNSYLVANIA, ASSIGNORS TO CHARLES SHARPE AND EDGAR L. THOMSON.

Design No. 3,470, dated May 4, 1869.

DESIGN FOR THE PLATES OF A COOK'S STOVE.

The Schedule referred to in these Letters Patent and making part of the same.

To all whom it may concern:

Be it known that we, JOHN MARTINO, JACOB BEESLEY, and JOHN CURRIE, of the city and county of Philadelphia, and State of Pennsylvania, have originated a new Design for a Complete Cook-Stove, of which the following is a full, clear, and exact description, reference being had to the accompanying drawings, making part of this specification.

Figure 1, A, upper front, with heavy round corners, with panels beaded around the edge, and ornamented in the centre of French style nulls and pods. The centre of upper front, ornamented with a shield of the Elizabethan style, with pods connecting right and left ends. Also, four scrolls, extending from the two upper and two lower corners of the shield, and connecting with the pods on the right and left ends, another shield surmounting the former shield, with plain oval centre, connected with beaded scrolls, twisting over and under

former shield, of same style, the whole forming one beautiful design.

Figure 2, B, oven-door, with ornamented moulding, the surface of the door-panel of a slight curve, ornamented of same style as fig. 1, A.

Figure 3, C, end fire-door, ornamented with shield and scrolls.

Figure 4, D, front fire-doors, of same style as fig. 3, C.

What we claim as our invention, and desire to secure by Letters Patent, is—

The design for a complete cook-stove, herein set forth.

JOHN MARTINO. [L. S.]
JACOB BEESLEY. [L. S.]
JOHN CURRIE. [L. S.]
